(57) **CLAIM**

The ornamental design for an embeddable wireless sensor, as shown and described.

DESCRIPTION

FIG. 1 is a front top perspective view of an embeddable sensor showing our new design;

FIG. 2 is a rear bottom perspective view thereof;

FIG. 3 is a top view thereof;

FIG. 4 is a bottom side view thereof;

FIG. 5 is a front view thereof;

FIG. 6 is a rear side view thereof;

FIG. 7 is a right side view thereof; and

FIG. 8 is a left side view thereof;

FIG. 9 is an enlarged detail of a portion as defined by the dashed circle 9 in FIG. 1;

FIG. 10 is an enlarged detail of a portion as defined by the dashed circle 10 in FIG. 2;

FIG. 11 is an enlarged detail of a portion as defined by the dashed circle 11 in FIG. 13;

FIG. 12 is an enlarged detail of a portion as defined by the dashed circle 12 in FIG. 3; and,

FIG. 13 is a bottom end perspective view of the embeddable sensor of FIG. 1.

The dash-dash broken lines show portions of the embeddable wireless sensor that form no part of the claimed design. The dash-dot-dot-dash broken lines define the bounds of the claimed design and form no part thereof. The embeddable wireless sensor is shown with a symbolic break in its length. The appearance of any portion of the article between the break lines forms no part of the claimed design.
